UNITED STATES PATENT OFFICE

169,918

STOCKING

George C. Tait, Schillington, Pa.

Application December 27, 1951, Serial No. 17,839

Term of patent 14 years

(Cl. D47—7)

To all whom it may concern:

Be it known that I, George C. Tait, a citizen of the United States, residing at Schillington, Pennsylvania, have invented a new, original, and ornamental Design for a Stocking, of which the following is a specification, reference being had to the accompanying drawing, forming a part hereof.

Fig. 1 is a side view of a flat folded stocking showing my new design, and

Fig. 2 is a fragmentary rear perspective view of the stocking shown in Fig. 1 as it appears when warm.

I claim:

The ornamental design for a stocking, as shown.

GEORGE C. TAIT.
